His Attorney.

UNITED STATES PATENT OFFICE.

JONATHAN FORCE, OF LIVINGSTON, NEW JERSEY.

ARC DEVICE.

Original application filed March 1, 1922, Serial No. 540,276. Divided and this application filed October 5, 1923. Serial No. 666,831.

To all whom it may concern:

Be it known that I, JONATHAN FORCE, a citizen of the United States, residing at Livingston, county of Essex, State of New Jersey, have invented certain new and useful Improvements in Arc Devices (division of my application Serial No. 540,276, filed March 1, 1922), of which the following is a specification.

10 The present invention relates to devices in which an arc is operated in a gaseous atmosphere between electrodes of which either the negative electrode alone, or both electrodes, operate at incandescence.

15 It is the object of my invention to improve the operation and life of an incandescent electrode device.

In arc devices having electrodes operating at incandescence in an inert gas without 20 consumption by oxidation, as in the case of open air arcs, an electrical effect is apt to cause the electrodes to waste away or disintegrate if the gaseous pressure is too high. On the other hand, too low a pressure causes 25 accretion of the electrodes in such manner as to decrease the arcing distance between the electrodes. Either effect decreases the life of the devices.

As will be described hereinafter in detail, my improved arc device is provided with an auxiliary chamber connected by a suitable orifice with the main arc chamber and being so proportioned and constructed that the gas pressure in the main arc chamber is so regulated that the electrodes will neither disintegrate nor build up by electrical action.

The accompanying drawing illustrates in Fig. 1 one embodiment of my invention in 40 longitudinal section; and Figs. 2 and 3 illustrate a starting device applicable to this device.

The device shown in Fig. 1 is particularly intended to operate as a lamp and therefore 45 the electrodes 1, 2 are of substantially equal size, both electrodes consisting of a refractory metal preferably tungsten, and both ordinarily being operated at bright incandescence. These electrodes are carried by 50 conductors 3, 4, which may also consist of tungsten, and are sealed into the envelope 5, which consists of glass having substantially the same coefficient of expansion as tungsten. The tips 6, 7 of the conductors 3, 4 55 are bent at an angle to the rest of the con-

ductors and toward each other so as to make the gap between the juxtaposed electrodes 1, 2 shorter than the distance between the conductors 3, 4. The envelope 5 contains a gaseous or gasifiable material which at the 60 operating temperature of the lamp has a pressure high enough to enable an electrical discharge between the electrodes 1, 2 to assume the characteristics of an electric arc, the energy of the discharge being enough 65 to heat the electrodes to incandescence. For example, the bulb may contain a quantity 8 of mercury and a filling of an inert gas such as argon, or nitrogen. The wires 3, 4 are insulated from the mercury by insulating 70 coatings 9, 10 of glass or the like.

The container or bulb 5 ordinarily is elongated to provide a condensing space above the arc. Preferably there is provided a separate chamber 11 which is smaller than the main chamber and connected to the main condensing chamber 13 by a constricted orifice 12 which is in line with the trajectory of the blast of mercury vapor emanating from the arc between the electrodes 1, 2. 80 The mercury vapor blast enters this auxiliary chamber 11, where the vapor pressure is determined by the temperature of the walls of the auxiliary chamber. This chamber therefore functions to regulate the gaseous 85 pressure about the electrodes.

In order to prevent electrode disintegration during the operation of the arc, the parts of the device must be arranged and proportioned to enable the arc to operate 90 with a voltage consumption below a limiting value, depending on the character of the device, particularly the length of the arc. One of the conditions controlling the voltage drop between the electrodes is the pressure 95 of the gas or vapor in which the arc operates. By the addition of the chamber 11, the pressure may be maintained at a lower value. Consequently the arc will be stabilized at a lower voltage and the disintegration 100 of the electrodes will be largely suppressed.

The auxiliary chamber should be proportioned to maintain the gas in the device at a pressure which is neither so high as to 105 cause an increase of the arc gap by disintegration of the electrodes, nor so low as to cause accretion of metal upon the electrodes, and decrease of arc gap. Too small a chamber increases the pressure and too large a 110

chamber causes too much condensation and decreases the pressure. The constriction or throat should not be so small as to interfere with the return of condensed mercury nor so large as to admit so much mercury vapor that the chamber runs abnormally hot. In the case of an auxiliary chamber about one inch in diameter a throat of about $\frac{1}{16}$ inch diameter can be used.

At the end of the straight portions of the conductors 3, 4 and adjacent the electrodes 1, 2 are located particles 14, 15 of a material having a higher electron emissivity than the lead wires. For example, these beads may consist of tungsten containing thoria, or of metallic thorium, or an alloy of thorium. I prefer to use tungsten containing about 5% thoria. This material may be prepared as described in Coolidge Patent 1,082,933. The thoriated tungsten mass may be welded as a bead, or a short length of wire to the lead wires.

In the device illustrated in Fig. 1 both electrode leads are provided with thoriated tungsten for localizing the arc to permit operation with alternating current. When an incandescent arc device is intended for operation with direct current, the cathode conductor only need be provided with a material of high electron emissivity.

When a device constructed in accordance with my invention is placed into operation, for example, by producing a high potential discharge between the electrodes 1, 2, the arc starts from the thoriated particles, 14, 15, remains there for a short time until the electrodes 1, 2 become heated, and then jumps to the electrodes where it continues to steadily operate.

When the arc has once been started between the electrodes 1, 2 and therefore has heated these electrodes to incandescence, there is little or no tendency for the arc to desert the electrodes, but in the absence of the thoriated masses, the arc would tend to flicker. The high electron emission from the thoriated tungsten counteracts this tendency and promotes a smooth, steady operation of the arc. In my application Serial No. 540,276 claims are made on this feature of the described device.

Although the arc may be started by a high voltage discharge it is desirable in many cases to start the arc by a low-voltage auxiliary discharge. In Figs. 2 and 3 I have illustrated devices embodying my invention having conductors 24, 25 connected to the electrode conductors 6, 7 and extending downwardly at such an angle that a circuit may be completed between these conductors 24, 25 by tilting the bulb, as shown in Fig. 2 by full lines. When the lamp is tilted back slowly toward the position indicated by dotted lines, auxiliary arcs are formed at the terminals of the conductors 24, 25

with the mercury, thereby starting the main arc between the electrodes 1, 2. A restoration of the bulb to an upright position causes these starting arcs to lengthen and break.

What I claim as new and desire to secure by Letters Patent of the United States, is:—

1. An electric discharge device comprising a container, refractory arc-sustaining electrodes therein operable at incandescence, a liquid in said container adapted to be actively vaporized during the operation of an arc between said electrodes, and means for regulating the vapor pressure in said container to prevent substantial disintegration or accretion of metal on said electrodes during operation. 75

2. An electric discharge device comprising a main container, refractory arc-sustaining electrodes in said chamber, a vaporizable liquid therein, and a condensing chamber connected to said container by a constricted throat of such proportions that the flow of vapor therethrough is restricted while permitting the return of condensation liquid. 85

3. An electrical discharge device comprising an envelope consisting of a main chamber and a smaller auxiliary chamber connected with the main chamber by an orifice, electrodes in said main chamber of which the cathode consists of material adapted to emit electrons when heated, and a quantity of mercury, the orifice between said chambers being proportioned to restrict the entry of mercury vapor but permitting the return of condensed mercury to the main chamber, and the auxiliary chamber being proportioned to maintain by condensation the pressure of mercury vapor in said main chamber at a value at which the gap between said electrodes will remain of substantially constant length. 95

4. An electric lamp comprising an envelope providing a main chamber, electrodes of refractory metal mounted therein in close juxtaposition, a quantity of mercury in said container, and means providing a smaller auxiliary chamber connected to said main chamber by a conduit permitting exchange of vapor and condensed liquid, said auxiliary chamber being of such proportions that the pressure of mercury vapor will be regulated to cause stable operation of said lamp. 100

5. An electric arc device comprising an elongated container providing a main arc chamber, electrodes of refractory metal at one end of said container in close juxtaposition, a quantity of mercury in said container, a gas at substantial pressure therein, an auxiliary chamber of smaller size than said main chamber connected to said main chamber by a constricted conduit at the end of said container opposite said electrodes, said auxiliary chamber being proportioned to maintain during operation of said device the 125 130

pressure of vapor in said main container at a value which causes neither disintegration nor accretion of said electrodes.

6. An electric lamp comprising an elongated container, electrodes of tungsten mounted in close juxtaposition at one end of said chamber, of an auxiliary container of smaller size than said main container and

connected thereto by a throat of sufficient size to permit both the admission of vapor ¹⁰ and the return of liquid condensate, a quantity of mercury in said main chamber and a filling of gas.

In witness whereof, I have hereunto set my hand this 2d day of October, 1923.

JONATHAN FORCE.

pressure of vapor in said main container at a value which causes neither disintegration nor accretion of said electrodes.

6. An electric lamp comprising an elongated container, electrodes of tungsten mounted in close juxtaposition at one end of said chamber, of an auxiliary container of smaller size than said main container and connected thereto by a throat of sufficient size to permit both the admission of vapor and the return of liquid condensate, a quantity of mercury in said main chamber and a filling of gas.

In witness whereof, I have hereunto set my hand this 2d day of October, 1923.

JONATHAN FORCE.

Certificate of Correction.

It is hereby certified that Letters Patent No. 1,578,973, granted March 30, 1926, upon the application of Jonathan Force, of Livingston, New Jersey, for an improvement in "Arc Devices," were erroneously issued to the inventor, said Force, whereas said Letters Patent should have been issued to *General Electric Company, a corporation of New York*, said corporation being assignee of the entire interest in said invention, as shown by the records of assignments in this office; and that the said Letters Patent should be read with this correction therein that the same may conform to the record of the case in the Patent Office.

Signed and sealed this 11th day of May, A. D. 1926.

[SEAL.]

M. J. MOORE,
Acting Commissioner of Patents.
